ELECTRIC CONTROL APPARATUS FOR
FUEL BURNERS

Lawrence M. Persons, Des Moines, Iowa, assignor
to Penn Electric Switch Co., Des Moines, Iowa,
a corporation of Iowa

Application November 17, 1933, Serial No. 698,477

6 Claims. (Cl. 158—28)

The object of my invention is to provide an electric control apparatus for fuel burners which is simple, durable and comparatively inexpensive to manufacture.

5 A further object of my present invention is to provide a control apparatus for a fuel burner which has circuit arrangements for quickly shutting down operation of the burner when combustion fails after occurring, initial failure of combustion operating to shut down the control apparatus only after a period of time.

Still a further object is to provide control apparatus in which a lock-out switch is opened by delayed action actuating means if combustion does not occur, or by a magnetic safety trip mechanism if combustion does occur but thereafter fails, the safety trip mechanism being energized by contacts of a combustion switch which have the peculiarity of closing only after the 15 combustion switch moves from cold to hot position and then returns toward cold position, such peculiarity being effected by a frictional mounting for one of the contacts.

Another object is to provide a control circuit 25 for a fuel burner wherein the ignition mechanism is de-energized by an ignition trip mechanism cooperating with a relay in such fashion that regardless of whether the relay is energized or de-energized, the ignition contacts remain 30 closed but are opened by the ignition trip mechanism, this being possible only when the relay is energized and has accordingly moved the ignition contacts to a position where they can be tripped by the ignition trip mechanism when it 35 is energized.

A further object is to provide the ignition trip mechanism in the form of a magnet attracted armature and contacts, one of which is the armature and which is so arranged that after the 40 ignition trip mechanism operates, current no longer flows through it.

Still a further object is to provide a relay and a running circuit through its entire coil, the safety trip mechanism being energized by connecting it across a part of the relay coil, the relay coil thus acting as an auto transformer for supplying current to the safety trip mechanism.

Still a further object is to provide a peculiar 45 type of contact mechanism operated by an oscillating element and arranged so that contacts are kept separated from each other when the oscillating element moves in one direction, but are engaged and then separated when the oscillating element moves in the opposite direction.

With these and other objects in view my in-

vention consists in the construction, arrangement and combination of the various parts of my device, whereby the objects contemplated are attained, as hereinafter more fully set forth, pointed out in my claims, and illustrated in the 5 accompanying drawings, in which:

Figure 1 is an electrical diagrammatic view of a control apparatus embodying my invention.

Figures 2 to 6 illustrate successive opening and closing positions of various contacts of the combustion switch of my control apparatus.

Figures 7 and 8 illustrate successive views in. 10 the operation of the relay switch; and Figure 9 is a simplified diagrammatic illustration of the 15 system.

On the accompanying drawings, the combustion switch comprises briefly a bimetal coil 11 for rotating a rod 13 having a ratchet 15 thereon. The ratchet 15 coacts with a leaf spring 17 for 20 swinging it to various circuit controlling positions.

The swinging of the leaf spring 17 controls starting contacts 18, ignition trip contacts 12 and safety trip contacts 14.

One of the contacts 14 is mounted on an arm 21 25 which is frictionally pivoted. An extension 17a of the leaf spring 17 is adapted to actuate the arm 21 and also an arm 21a on which the lower contact 14 is mounted. The parts 11, 13, 15 and 17 operate as disclosed in the Williams Patent No. 30 1,827,703, of October 13, 1931.

The relay switch has ignition contacts 16, motor contacts 18 and 20 and holding contacts 22. These are operated by an armature 19 attracted by either one or both coils 26 and 28 of the relay 35 switch.

An ignition trip mechanism is associated with the relay switch and comprises a magnet 30, an armature 32 which constitutes also a contact and a cooperating contact 34. The contact 34 is 40 mounted on a spring 35 with which one of the contacts 16 is associated and which has an extension 37 to coact with a bridging member 39 of the contacts 18 and 20.

The contacts 18 and 20 are in series and one 45 set only of them need be provided, but the arrangement shown is used in order to eliminate pig-tail connections.

The lock-out switch of my control apparatus has normally closed contacts 36 which may be 50 opened by a spring urged cam 38 when it is released by a bimetal latch 40.

Practical operation

In the operation of my control apparatus, the 55

parts are normally in the position of Figure 1. When a room thermostat connected with terminals R and R' closes because of lowering of the temperature surrounding the room thermostat to a predetermined degree, a starting circuit is established.

Starting circuit

The starting circuit may be traced in Figure 9 from the lower end of the secondary coil of a transformer 9, which supplies low voltage current for the various control circuits, through the terminal R', wire a, the room thermostat R. T., wire b including terminal R and then through the coil 28 of the relay and wire d to a lock-out switch heater 42 and return through wires e and f to the upper end of the secondary coil of the transformer, going through the normally closed starting contacts 10 of the combustion switch.

This causes the armature 19 of the relay switch to be attracted and the lock-out switch heater 42 to start heating. Attraction of the armature 19 closes the motor contacts 18 and 20 for energizing the burner motor through wires g, h, i, and j and leaves the ignition contacts 16 closed, the ignition circuit then being traceable through wires g, h and i and wires k, l and m and through the motor contacts 18 and 20, which upon closing, energize the ignition circuit.

The normal tendency for the ignition contacts 16 is to open when the relay is energized, but they are held closed by the armature 32 of the ignition trip mechanism.

In case combustion does not occur, the heat dissipated from the lock-out switch heater 42 will, after a time period, trip the lock-out switch so that the burner is shut down until the trouble is remedied and the lock-out switch reset manually. If combustion does occur however, the contacts 10 will be opened, as in Figure 2, thus cutting the lock-out switch heater 42 out of circuit.

Running circuit

Attraction of the armature 19 also closes the holding contacts 22 whereupon the current flowing from wire b into the right end of the coil 28 of the relay will flow out of the left end of the coil 26, through wires n and o and then through the contacts 22 and wire p back to the upper end 50 of the secondary coil of the transformer.

Ignition and trip circuit

This circuit may be traced from the terminal R and wire b through the contacts 34 and 32, 55 through the magnet 30 and wire q and then through the contacts 12 of the combustion switch and wire f to the transformer. The contacts 12 are closed when combustion occurs, as illustrated in Figure 2. Closing of these contacts energizes the magnet 30 so that the armature 32 swings from the position of Figure 7 to the position of Figure 8, thus permitting the ignition contacts 16 to open and the ignition and trip circuit to be opened because of the contacts 32 and 34 being separated.

Combustion causes the combustion switch to move further from the position of Figure 2 to the position of Figure 3 which swings the frictionally mounted arm 21 downwardly, thus keeping the contacts 14 open during the entire movement of the combustion switch from cold to hot position. On the return movement, as in Figures 4, 5 and 6 however, it will be noted that the contacts 12 are first opened so that they are in position for initial operation and then the contacts 14 are

closed, whereafter the contacts 10 close for initial operation. Finally the position of Figure 1 is assumed wherein the contacts 14 are disengaged.

Safety trip circuit

During normal operation, the room thermostat, when its contacts open, will entirely open the secondary circuit of the transformer, thus shutting down all circuits through the relay switch, lock-out switch heater and combustion 10 switch so that the return movement of the combustion switch to normal position has no effect.

In case of combustion failure after it is once established however, it is desirable in a lock-out type of control apparatus to operate the lock-out 15 switch and this is accomplished by the safety trip contacts 14 and a magnet 43. When the position of Figure 5 is assumed by the combustion switch, the contacts 14 are engaged whereupon current flows through wires a, b, d, r, s, o and p and through R. T., 28, the magnet 43 and contacts 22 cause the magnet to attract the bimetal latch 40 and immediately operate the lock-out switch so that it will have to be manually reset.

The particular frictional mounting of the arm 25 21 of the combustion switch provides that the contacts 14 will remain open during the entire movement of the combustion switch from cold to hot position so that the safety trip magnet 43 does not become energized. It becomes energized 30 only when the room thermostat is still calling for heat, but the combustion switch, because of combustion failure, returns to the position of Figure 5 and finally to the position of Figure 1 wherein these contacts which are no longer needed are separated so that the combustion switch can operate initially in the normal manner.

With respect to the frictionally mounted contact arm 21 and the peculiar movement imparted to it and to the arm 21a for engaging and separating the contacts 14, this is a novel feature not heretofore used in switches. Essentially the actuating element 17a causes the frictionally mounted arm 21 to move in a direction for engaging the contacts 14, the contacts 12 first engaging 45 each other and then the arm on which the lower contact 12 is mounted engaging the arm 21 to cause such movement, as shown in Figure 2. The element 17a then engages the arm 21a to move the lower contact 14 in a separating direction so that during the downward movement of the actuator 17a, the contacts 14 do not become engaged.

When the element 17a moves in an opposite direction, however, the contacts 14 are first permitted to engage as in Figure 5 and then the arm 21 is engaged, as in Figure 6, whereafter as in Figure 1, the contacts 14 are separated. Thus it is possible to maintain an open circuit through contacts 14 when the actuator moves in one direction and both close and open such circuit when the actuator moves in an opposite direction.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a control system for a fluid fuel burner 70 and its fuel feeding means; a control circuit including an igniter, a motor for controlling fuel feed, a multiple contact relay operable when energized to close contacts energizing said motor and igniter and to urge contacts controlling en- 75

ergization of said igniter, which are closed when said relay is de-energized, towards open position, an electrically operable latch mechanism holding said ignition contacts closed when de-energized 5 and a combustion responsive switching mechanism having contacts which are closed upon the establishment of combustion controlling energization of said latch mechanism.

2. In a control system for a fluid fuel burner 10 and its fuel feeding means; a control circuit including an igniter, a motor for controlling fuel feed, a multiple contact relay operable when energized to close contacts energizing said motor and igniter and to urge contacts controlling energization of said igniter, which are closed when said relay is de-energized, towards open position, an electrically operable latch mechanism holding said ignition contacts closed when de-energized 15 and a combustion responsive switching mechanism having contacts which are closed upon the establishment of combustion controlling energization of said latch mechanism. said electrically operable latch mechanism including a pair of contacts in the circuit of the mechanism and operable to separated position upon energization of the mechanism.

3. In a control system for a fluid fuel burner and its fuel feeding means, a control circuit including an igniter, a motor for controlling fuel 20 feed, a lock-out switch, a multiple contact relay operable when energized to close contacts energizing said motor and igniter and to urge contacts controlling energization of said igniter, which are closed when said relay is de-energized, toward 25 open position, electrically operable actuating means for said lock-out switch, an electrically operable latch mechanism holding said ignition contacts closed when de-energized and a combustion responsive switching mechanism having contacts 30 which are closed upon the establishment of combustion, controlling energization of said latch mechanism and contacts which are open before combustion is established and remain open while it is being and after it is established and which 35 are closed only upon subsequent failure of combustion, said last mentioned contacts controlling energization of said actuating means.

4. In a control system for a fluid fuel burner and its fuel feeding means, a control circuit including an igniter, a motor for controlling fuel feeding, a lock-out switch, a multiple contact relay operable when energized to close contacts energizing said motor and igniter and to urge 40

contacts controlling energization of said igniter which are closed when said relay is de-energized, toward open position, delayed action actuating means for tripping said lock-out switch and an electro-magnet for also tripping it quickly when energized, an electrically operable latch mechanism holding said ignition contacts closed when de-energized and a combustion responsive switching mechanism having contacts which are closed upon the establishment of combustion, controlling 45 energization of said latch mechanism, other contacts opened upon the establishment of combustion effecting de-energization of said delayed action actuating means and still other contacts which are open before combustion is established 50 and remain open while it is being and after it is established, and which are closed only upon subsequent failure of combustion, said last mentioned contacts controlling energization of said electro-magnet.

5. In a control system for a fluid fuel burner, and its fuel feeding means, a control circuit including a motor for controlling fuel feed, a lock-out switch, a multiple contact relay operable when energized to close contacts energizing said motor, electrical actuating means operable when energized to immediately open said lock-out switch, and a combustion responsive switching mechanism having contacts which are open before combustion is established and remain open 30 while it is being and after it is established and which are closed only upon subsequent failure of combustion, said last mentioned contacts controlling energization of said actuating means.

6. In a control system for a fluid fuel burner 35 and its fuel feeding means, a control circuit including a motor for controlling fuel feeding, a lock-out switch, a multiple contact relay operable when energized to close contacts energizing said motor, delayed action actuating means for tripping said lock-out switch and an electro-magnet for also tripping it quickly when energized, and a combustion responsive switching mechanism having contacts closed upon the establishment of combustion effecting de-energization of said de- 40 delayed action actuating means and other contacts which are open before combustion is established and remain open while it is being and after it is established and which are closed only upon subsequent failure of combustion, said last mentioned 45 contacts controlling energization of said electro-magnet.

LAWRENCE M. PERSONS.
